CATAMENIAL BANDAGE

Filed Feb. 26, 1931

BY ATTORNEY

UNITED STATES PATENT OFFICE

JACOB JOSIAS, OF BROOKLYN, NEW YORK

CATAMENIAL BANDAGE

Application filed February 26, 1931. Serial No. 518,813.

This invention relates to new and useful improvements in a catamenial bandage.

It is general construction to arrange catamenial bandages with a liquid-proof holder to receive and hold a napkin. The napkin is generally placed within the holder so that its top face is substantially flush with the contacting surface of the holder. When applied, the napkin engages against the body and against the orifice. While the napkin absorbs liquids discharging and dripping down, it is not tight enough against the body to absorb all odors.

It is an object of this invention to supplement the regular napkin in a catamenial bandage with a top narrower napkin section in a manner to naturally press against the body and absorb odors as well as liquids.

A still further object of this invention is to arrange the supplementary napkin removable for replacement when soiled selectively from the main napkin.

The invention furthermore proposes as an object to provide top straps beneath which the supplementary napkin may be slipped in as constituting the means for removably supporting the latter napkin section.

A still further object of this invention is to construct the catamenial bandage so that the ends of the supplementary napkin may engage through the same, holding apertures that serve to secure the main napkin.

The invention still further proposes to provide adjustable means for aiding in pressing the material of the supplementary napkin against the orifice.

It is further proposed to construct said adjusting means removable.

A still further object of this invention is to construct a device of the class mentioned which is of simple durable construction, dependable in use and efficient in action, and which can be manufactured and sold at a reasonable cost.

For further comprehension of the invention, and of the objects and advantages thereof, reference will be had to the following description and accompanying drawing, and to the appended claims in which the various

novel features of the invention are more particularly set forth.

In the accompanying drawing forming a material part of this disclosure:—

Fig. 1 is a perspective view of a device constructed according to this invention. 55

Fig. 2 is an elevational view of Fig. 1.

Fig. 3 is a plan developed view of the napkin holder per se.

Fig. 4 is a fragmentary enlarged sectional view taken on the line 4—4 of Fig. 3. 60

Fig. 5 is a transverse sectional view taken on the line 5—5 of Fig. 3.

Fig. 6 is a fragmentary enlarged detailed view of a portion of Fig. 1, showing in particular the connection between the napkin support and the body belt, seen as though looking along the line 6—6. 65

Fig. 7 is a view similar to Fig. 5, but showing the means which aids in the pressing of 70 the supplementary napkin against the body in place.

Fig. 8 is a fragmentary elevational view looking in the direction of the line 8—8 of Fig. 7. 75

Fig. 9 is a sectional view taken on the line 9—9 of Fig. 7.

As shown on the drawing the catamenial bandage has a belt portion 10 for engaging around the waist of a wearer. This belt portion is not illustrated in detail nor described, since it forms no part of this invention and is generally known to the public. Attached upon the belt portion there is a napkin holder 11. 80

This napkin holder comprises a liquid-proof sheet in the form of a strip of substantially U-shape in cross section for receiving a napkin 12 so that the top of the napkin is substantially flush with the top of the strip. The sheet is bent along both edges from end 90 to end and transverse cloth binding strips 13 are secured upon the ends of the strip for holding it in the substantial cross section mentioned. In Fig. 5 the cross section will be seen in detail and it should be noticed that 95

the top edges, indicated by reference numerals 14, are bent over so as to partially extend across the top of the napkin 12. The bent top edge 14 may be reinforced by a strip amalgamated upon the said edge to pre- 100

vent the latter from bulging when the catamenial bandage is in use.

A means is provided upon the ends of the strip for attaching it upon the belt 10. This 5 means, as shown on the drawing, is in the form of hook elements 15 attached upon the ends of the strip upon the transverse cloth strips 13 and engageable with eyelets 16 attached upon the belt 10. While this 10 particular means has been illustrated, it is not intended as a limitation since other conventional means may be used which may include adjustments so as to change the tension of the napkin holder. The sanitary napkin 15 12 has its ends reduced, indicated by reference numerals 17, and passed through apertures 18 formed in the base portion of the strip and constituting the means for holding the napkin in place. A reinforcement 20 ring 19 is amalgamated upon the strip around the opening 18 so as to reinforce the opening. The napkin 12 may be of any of the standard ones used on the market and treated with proper deodorizing chemicals. 25 Transverse straps 20 extend across the top of the napkin holder and join the edges of the strip so as to prevent accidental opening of the holder. The napkin 12 is slipped beneath these straps 20 when inserted in place. 30 A means is also provided for holding a supplementary napkin, such as indicated by reference numeral 21, which is of smaller width than the napkin 12 above the top of the said strip. This means is in the form 35 of other transverse straps 22 substantially over the straps 20 and also transversely arranged and connected upon opposite edges of the strip of material, which forms the napkin holder. The ends 23 of the supplementary 40 napkin section 21 are also reduced and are engaged through the openings 18 so as to aid in maintaining this section in place. The loose ends 17 and 23 are placed in a pair of transverse straps 19' at the bottom of napkin 45 holder 11.

A means is also provided for aiding in pressing the material of the supplementary napkin 21 better against the body. This means is in the form of hooks 24 attached 50 upon the top edges of the strip which forms the napkin holder directly opposite each other. A transverse strap 25 is provided with eyelets at its ends for engagement by the hooks 24 so that the strap may assume a position 55 between the napkin 12 and the napkin section 21 as clearly shown in Fig. 7. In Figs. 2 and 5 the device is shown with the strap 25 removed. A hollow resilient member 26 is attached upon the strap 25 at two 60 diametrically opposite sides by means of short legs 27. The other portions of this hollow member are opened so that cotton material 28 may be forced within the hollow member 26 to pack the interior to any desired degrees 65 so as to project the top apex 28 of the hollow

member as desired. A recess 29 is disposed between the apex 28 and the outer diameter of the resilient member. A plurality of apertures 30 connect this recess with the interior of the device. 70

When the catamenial bandage is used with the hollow resilient member 26, it is necessary to first properly pack it with cotton or other absorbent material preferably impregnated with suitable chemicals. Then the strap 25 is positioned beneath the napkin section 21 and above the napkin section 12. When the bandage is worn, the parts should be so positioned that the hollow resilient member 26 acts against the orifice. 75

When the catamenial bandage is worn without the strap 25, the napkin section 21 which is of small width will act against the body. It is pointed out that this section of small width can fit more snugly against the body as is desired. It will serve to absorb odors as well as liquids. When this section becomes soiled, it may be replaced without replacing the napkin 12 if the latter member is 80 not soiled. 85

While I have shown and described the preferred embodiment of my invention, it is to be understood that I do not limit myself to the precise construction herein disclosed and the right is reserved to all changes and modifications coming within the scope of the invention as defined in the appended claims. 90

Having thus described my invention, what I claim as new, and desire to secure by United States Letters Patent is:— 100

1. A napkin holder, comprising a napkin holder, comprising liquid-proof sheet material in the form of a strip of substantially U-shape in cross section for receiving a napkin so that the top of the napkin is substantially flush with the top of the strip, means for holding supplementary napkin of smaller width than said napkin above the top of the said strip, and adjustable means on the longitudinal edges of said strip for aiding in pressing the material of the supplementary napkin against the body. 105

2. A napkin holder, comprising a napkin holder, comprising liquid-proof sheet material in the form of a strip of substantially U-shape in cross section for receiving a napkin so that the top of the napkin is substantially flush with the top of the strip, means for holding supplementary napkin of smaller width than said napkin above the top of the said strip, and adjustable means on the longitudinal edges of said strip for aiding in pressing the material of the supplementary napkin against the body, comprising a strap attached at its ends upon the edges of said strip, a hollow resilient member on said strap formed with side openings so that the interior is accessible for receiving cotton or other absorbent material, and the top of said hollow member being formed with an apex 115

surrounded by a recess having apertures communicating with the interior.

3. A napkin holder, comprising a napkin holder, comprising liquid-proof sheet material in the form of a strip of substantially U-shape in cross section for receiving a napkin so that the top of the napkin is substantially flush with the top of the strip, and means for holding supplementary napkin of smaller width than said napkin above the top of said strip, comprising transverse straps attached across the edges of said strips, other transverse straps being connected across the edges of the strip also for holding the main napkin in place, and the said strip being also formed with apertures for receiving reduced ends from both of said napkin sections, and other transverse straps at the bottom of the said napkin holder for holding the reduced ends of the napkin sections.

In testimony whereof I have affixed my signature.

JACOB JOSIAS.
